3,005,118 ELECTRIC MOTORS

Emil L. Ranseen, deceased, late of Chicago, Ill., by Agnes J. Ranseen, executrix, Chicago, Ill., assignor, by decree of distribution, to said Agnes J. Ranseen
Original application July 16, 1954, Ser. No. 443,798, now Patent No. 2,797,346, dated July 25, 1957. Divided and this application June 20, 1957, Ser. No. 667,008

16 Claims. (Cl. 310—49)

This invention relates to improvements in electric motors of the impulse type. By that term is meant motors which are of construction such that their operation is produced by successive impulses of current delivered to the motor either in regular timing or at various pauses between successive impulses. Such motors are also of such construction that each impulse of current delivered to the motor produces a known and pre-determined angular advance of the rotor, under normal conditions of motor operation.

One feature of the invention concerns itself with the provision of a construction of stepping motors of that type in which the rotor teeth extend radially into the axial alignment with the stator teeth so that special provision must be made in the structure of the device to enable assembly of the successive stator and rotor elements endwise and in proper sequence of such assembly, thus avoiding the need of splitting the rotor and stator elements on a plane or planes parallel to the shaft.

Other features concern themselves with various means to produce proper sequential delivery of the pulses of current to the several stator exciting coils. In this connection there is disclosed several forms of commutation devices driven by the rotor itself, so that as such rotor rotates the incoming pulses or steady current supply are or is delivered to the exciting coils in the proper sequence. These improvements also include means to vary or adjust the phasing of the pulses delivered to the several stator coils for various purposes and results.

A further feature of the invention relates to the provision for controlling the rate of magnetization of demagnetization of the stator coils for various reasons and purposes related to the functioning of the motor. In this connection there is disclosed capacitor and resistor arrangements by which the decay time of the magnetization can be brought to an optimum condition, taking account of the rate at which the pulses are required for motor operation.

Still another feature relates to the provision of flexible clutch means intermediate between the rotor shaft of the motor and a driven load, such as a load of large mass of which the momentum is large, to enable bringing such large mass load into speed, such mass being so large that a considerable time must elapse before the torque delivered by the stepping motor can bring such mass into intended rate of movement. There is a special relation between the effects produced by such flexible clutch when interposed between a stepping motor drive and the load, as differentiated from bringing such load into motion by use of a conventional substantially steady torque motor.

A further feature of the invention relates to the provision of special means to lock the rotor against rotation at conclusion of a series of stepping impulse produced advances. In this connection provision has been made for retaining the energizing current on that one of the several stator coils which will produce the locking at the desired pulse, or at conclusion of response to a pre-determined number of delivered pulses. Such retention of the current on such stator coil will strongly lock the rotor in the desired position.

2

Another feature of the invention relates to the provision of an adjustable friction drag in connection with the rotor, so that tendency for such rotor to over-ride when receiving rapid pulses will be balanced and such over-riding will be avoided.

Other objects and uses of the invention will appear from a detailed description of the same, which consists in the features of construction and combinations of parts hereinafter described and claimed.

10 In the drawings:

FIGURE 1 shows a perspective view of one form of motor embodying various of the features of invention, this figure being in partial section;

15 FIGURE 2 shows a longitudinal section corresponding to FIGURE 1, but in blasted form;

FIGURE 3 shows a face view of a modified form of rotor polar element;

20 FIGURE 4 shows a commutator unit which may be either manually driven or driven by the rotor for control of energization of the stator coils of a motor embodying features of the present invention;

25 FIGURE 5 shows schematically the three coils of a typical three section stator element of a motor embodying features of the present invention, and with said coils connected together in delta connection, for supply of three phase A.C. to said coils when the motor is to be operated by such a current supply;

30 FIGURE 6 shows schematically a modified arrangement of stator coils of a motor embodying features of the present invention, in which modification each stator coil is subdivided into two sections, and each such section is centrally tapped, all such coil elements being ring or delta connected together, together with a commutator suitable for combination with such a sectionalized coil arrangement;

35 FIGURE 7 shows a fragmentary perspective view of a portion of the stator element showing how the blocks which sub-divide the gap between the two poles of the stator may be conveniently supported;

40 FIGURE 8 shows a fragmentary perspective view of a portion of the stator element showing how laminations of said stator element may be conveniently supported in a suitable structure to establish a portion of the true polar element;

45 FIGURE 9 shows a fragmentary perspective view of a portion of the rotor element showing how laminations may be supported in the periphery of a rotor plate;

50 FIGURE 10 shows a fragmentary perspective view of a portion of the stator element showing how laminations of said stator element may be conveniently supported in a suitable structure to establish the stator formation between two of the coils, and this figure may be considered as being complementary to the showing of FIGURE 8;

55 FIGURE 11 shows a fragmentary perspective view of a modification of the embodiment shown in FIGURE 2;

FIGURE 12 shows a longitudinal view partly in section, of another modified embodiment of the features of the present invention, in which modification the stator is located within the rotor;

60 FIGURE 13 shows a fragmentary half section longitudinally through another modified embodiment of the invention;

FIGURE 14 shows a fragmentary cross-section taken on the line 14—14 of FIGURE 13, looking in the direction of the arrows;

65 FIGURE 15 is a schematic showing of a motor embodying features of the present invention with its motor shaft coupled to a high inertia load, such as the table of a machine tool, such coupling being effected through the medium of a flexible coupling of construction such as to allow for a small angular displacement of the driv-

ing end without corresponding displacement of the driven end;

FIGURE 16 shows more or less schematically, and in perspective, some of the commutating elements by which a motor may be controlled for various conditions of operation; and the elements shown in this figure will be better understood by reference to FIGURE 21 which is a schematic wiring diagram to be read in connection with FIGURE 16;

FIGURE 17 shows, more or less schematically, a motor embodying features of the present invention, and provided with a commutator arrangement for control of current delivery to the several stator coils in proper sequence, and this figure also shows a friction brake interposed between the rotor and the driven load;

FIGURE 18 shows schematically a simple circuit arrangement for use in connection with the motor arrangement of FIGURE 17, including the commutation elements thereof;

FIGURE 19 shows a longitudinal fragmentary section through the commutator end of a motor embodying the features shown in FIGURE 16, this figure showing the commutation arrangements for one of the three stator coils;

FIGURE 20 shows an end view corresponding to FIGURE 19;

FIGURE 21 shows a schematic wiring diagram of the stator coils, the commutation elements, and the switching gear of the arrangement shown in fragmentary form in FIGURE 16 and also shown in FIGURES 19 and 20;

FIGURE 22 shows a portion of the commutating elements for a three stator coil motor, in which commutating elements use is made of a rotor shaft driven cam element and co-operating switch elements such as micro-switches;

FIGURE 23 shows a schematic wiring diagram including the commutation elements shown in FIGURE 22; and

FIGURE 24 shows schematically a single stator coil and capacitors (and a resistor) connected across such coil, being a modified arrangement as compared to other coil arrangements also illustrated herein, such modifications enabling operation with a smaller loss of energy than will occur with previously illustrated arrangements.

Referring first to FIGURES 1 and 2, there is therein shown a typical motor construction embodying certain of the features of novelty herein disclosed. The motor shown in these two figures, and elsewhere, includes three stator elements and corresponding rotor elements, and is so devised that rotor rotation may be produced in either direction. This construction includes an energizing coil for each stator element, and the teeth of the several stator and rotor elements are so related and positioned that by energizing the stator coils in succession the steps of rotor advancement will be sequential, three steps comprising a group, and each stator coil being energized at its proper sequential position in such group. By energizing the three stator coils in either sequence, such as "A," "B," and "C" or "A," "C," and "B," the direction of rotation can be determined. Various other features and functions will appear as the motor construction is detailed.

Herein disclosed are several means and arrangements for controlling the delivery of the impulses to the several coils. These are now disclosed as follows:

The current impulses must be delivered to the several stator coils in an orderly and predetermined sequence to effect rotor rotation in either direction. The successive impulses may be delivered to the stator coils at equal and predetermined intervals, or at unequal intervals, but in that order or sequence which corresponds to a desired direction of rotation. Or, as may sometimes happen, the impulses may come in what may be termed a two directional sequence, some of the impulses corresponding to rotation in one direction, and some to rotation in contrary direction. This might be true, for example, in an installation in which an algebraic sum of positive and nega-

tive digits was to be obtained, including therefore some impulses corresponding to forward rotation, and some corresponding to reverse rotation.

It is also to be noted that the impulses may be delivered to the stator coils under such controls as suggested above, either with the origination of the impulses at some remote location, and by an impulse generator completely independent of the motor itself, or said impulses may be created by the motor itself by means of some element or unit rotating in harmony with and under control of, the advancements of the rotor itself. Such an arrangement might take the form of a commutation element physically connected to and driven by the rotor, and provided with means and contacts whereby the connections to the stator coils would be effected in the manner and the sequence desired or required.

In FIGURE 5 there are shown the three stator coils as "A," "B" and "C," corresponding to the three coils of FIGURES 1 and 2, for example. These coils are shown in delta connection, for simplicity, and the three delta terminals are shown at 188, 189 and 190. These are brought to the switch contacts 191, 192 and 193 by which delivery of the three phase current to the three motor terminals in selected order is effected.

In FIGURE 15 there is shown another embodiment of a three phase current supply to the motor coils, and in this case there is illustrated a typical industrial application of the motor to a service for which it may be well adapted. In this case the motor is designated generally by the numeral 194, its stator coils by the numerals 195, 196 and 197, and the rotor shaft by the numeral 198. The coils are conveniently delta connected, their coil terminals being shown at 198, 199 and 200, respectively. The reversing control switch 201 is illustrated, being connected in conventional manner for reversal of two of the supply phases in order to effect reversal of rotor rotation.

The motor illustrated in this figure is provided with a large number of stator and rotor teeth, so that the angular advance produced by each current impulse is correspondingly small. Furthermore, if desired, this motor may be provided with the multiple tooth arrangement such as shown in FIGURES 13 and 14, so that even when using such large number of teeth per revolution and small angular advancement per step a high torque may be developed.

In FIGURE 15 the work to which this motor is connected comprises such an element as the machine tool table 202 riding on the ways 203 (only one of which is shown). The table is provided with the rack bar 204 which is engaged by the pinion 205 carried by the stub shaft 206. The coupling 207 connects the motor shaft 198 to this stub shaft 206 so that slight angular displacements may occur between the motor shaft and said stub shaft, but without permanent angular displacement of the two shafts with respect to each other. Thus, assuming that the work has a large mass and correspondingly large inertia, as the motor coil is subjected to a current impulse its advancement may immediately commence, the coupling yielding slightly to allow the rotor to get under way and develop torque and build up the force acting to accelerate the work, and the movement of the work may thus be increased while preventing any "stalling" of the rotor to occur. When the work has thus been accelerated to speed the delivery of the impulses to the stator coils, with the work under movement, will occur without material angular displacements occurring within the coupling itself. This general operation has been described on the assumption that the current supply to the motor is a conventional three phase supply. It will be evident, however, that similar advantages produced by the features of motor construction hereinbefore disclosed which enable production of high torques combined with relatively small angular advancements per impulse may be made available even when the impulses are delivered to the stator coils otherwise than as conventional three phase

wave form impulses. For example, the impulses may be delivered at non-uniform intervals to such motor, from any suitable impulse generator, and under suitable controls, and as each step of the rotor is urged the torque developed will be large in comparison to the overall dimensions of the unit.

The following comments concerning the acceleration of a heavy or large inertia load by a stepping motor are in order:

As each pulse is delivered to a section of the motor a torque is transmitted to the input end of the coupling 207. Such coupling may then yield slightly, delivering to the output end of the coupling and to the shaft 206 a heavy momentary torque. During the slight time lapse until the arrival of the next pulse the flexible element of the coupling will continue to urge the shaft forward with decreasing torque until the next pulse arrives at the next section of the stepping motor. Then another shock torque may be delivered to the input end of the coupling, again raising the torque delivered to the shaft 206 and further slightly accelerating its movement. However, if the advance of the shaft 206 under the urge of the first pulse was very slight (due to the high inertia of the driven load), the motor rotor would not have advanced sufficiently to enable the rotor teeth of the second section of the motor to develop a forward torque, and such second pulse would not deliver any further forward acceleration to the parts so that when the third motor section should next be energized it might even develop a reverse torque, driving the rotor backwardly to approximately but not quite its original position. Then when a succeeding pulse should next come to the first coil of the series a new forward shock torque would be delivered to the input end of the coupling. The preceding pulses would, however, have produced some slight advance of the shaft 207 so that this new pulse delivered to the first coil of the series would now be more effective than preceding pulses and the shaft 206 and load driven thereby would respond more than before to the urge of the flexible coupling. By maintaining the pulses in the proper sequence the shaft 206 (and load) would gradually gain speed until the rotor speed would be such as to synchronize the advances of its rotor teeth with the incoming of the pulses. Then a continuous drive of the shaft 206 (and load) would proceed.

The above action is due to the presence of the flexible coupling 207 between the motor shaft and the driven load. Such action may be compared to the acceleration of a heavy load by delivering to it a regular succession of timed blows, each transferring a small amount of momentum to such heavy load in addition to the momentum previously gained by such load from the previous blows.

When the current is supplied to the motor unit by a non-impulse source, such as a battery or other D.C. supply, it is evident that provision must be made for causing the current to be delivered to the several stator coils in succession and according to the proper sequence in order to effect the continuous rotor advancement in selected direction. This may be done by provision of a suitable commutator having one of its elements drivingly connected to the rotor so that its position remains at all times phased with respect to the rotor itself. One simple form of such arrangement is shown schematically in FIGURE 4 and also in FIGURE 17. In this case the stator coils are shown at "A," "B," and "C," of FIGURE 4 and the drive shaft is indicated at 208. This shaft may be the motor shaft itself, or may be otherwise driven. It is shown as provided with the gear 209 driving the pinion 210 on the stub shaft 211 journaled in the bracket 212. This stub shaft carries the arm 213 extending radially from the disk portion 214. Said arm carries the brush carrier 215 which carries the inwardly reaching brush 216 which may ride on the commutator segments 217 of a stationary commutator unit 218 supported by the bracket 219. If desired such support of the unit 218 may be

effected by a stub shaft 220 extended through the bracket so that angular adjustments of the unit 218 may be made to ensure correct energization of the various segments in phase with the rotor advancements. The stator coils 5 are shown as being star connected with one end of each coil connected to the common terminal 221. The commutator unit 218 is provided with a number of segments which is a full multiple of the number of sections of the stepping motor (being three sections in certain of the embodiments herein illustrated). Thus each rotation of the stub shaft 211 by drive of the pinion 210 causes excitation of the segments in proper sequence to cause rotor advance an angular amount equal to the angular spacing between center to center of successive stator teeth 10 of a section. The disk portion 214 of the element carried by the stub shaft 211 carries the circular contact 222 which is connected to the brush 216 by a suitable conductor, not shown in FIGURE 4. A brush 223 carried by the bracket 212 engages the said contact 222 to deliver or receive current during the entire rotation of the stub shaft 211 and pinion 210. A source of current, such as the battery 224 has its terminals connected by the leads 221 and 225 to the common terminal of the stator coils and to the brush 223. Thus each rotation of the pinion 210 under drive from the rotor element of the motor will ensure supply of current to the three stator coils "A," "B" and "C" in sequence. The correct timing of the coil energizations may be ensured by phasing the stub shaft 220 in the one direction or the other as needed.

Now it will be seen that each revolution of the pinion 210 corresponds to a complete cycle of excitations of the stator coils or to a full multiple of such complete cycle. Reference to the showing of FIGURES 1 and 2 shows that one "cycle" of the stator coil excitations must correspond to the angular displacement between two consecutive stator teeth of any one of the sections "A," "B" and "C." Thus it is necessary, when supplying the current impulses to the stator coils by use of a commutator arrangement such as that of FIGURE 4, to ensure one complete rotation of the stub shaft 223 of the commutator unit of FIGURE 4 for each rotor advancement of amount equal to the angular displacement between the successive stator teeth or to a full multiple of such angular displacement. Therefore, when there are twelve stator teeth, requiring twelve corresponding rotor "full" advancements per revolution it is seen that the brush 223 of the commutator unit of FIGURE 4 must execute twelve complete revolutions per rotor complete revolution in case the commutator 218 has only three segments; and since there are three "rotor steps" per "full" advancement it is seen that there will actually be thirty-six "steps" of the rotor per complete revolution. Also, there will, under the assumed condition, be twelve rotations of the stub shaft 223 and brush 216 per rotor revolution, requiring a gear ratio of twelve to one as between the gear 209 and the pinion 210.

In FIGURE 6 is shown schematically another form of commutator arrangement for ensuring delivery of the current impulses to the stator coils in proper sequence. In this case, however, the three stator exciting coils are each subdivided into two sections which are then centrally tapped. Thus each stator coil comprises in effect four sections which may be individually excited. Commutator bars are then provided corresponding to these coil sections, with suitable brush arrangements in connection with the commutator bars.

In this arrangement the three stator exciting coil units are designated as "A," "B" and "C"; and they are each composed of two sections "AA," "AAA," "BB," "BBB," "CC" and "CCC." The exciting units are delta connected. To this end the proximate ends of the successive sections are connected together into a ring by the leads 226, 227 and 228, the sub-sections of each section being connected together by the leads 229, 230 and 231. There are then provided twelve commutator bars, two for each

sub-section, numbered 232, 233, 234, 235, 236, 237, 238, 239, 240, 241, 242 and 243. The center points of the sub-sections are connected to the alternate commutator bars, as follows; AAA to 232; AA to 234; BBB to 236; BB to 238; CCC to 240; and CC to 242; by the leads 244, 245, 246, 247, 248 and 249, respectively. The ring leads 226, 227 and 228 are connected to the commutator bars 235, 239 and 243 by the leads 250, 251 and 252, respectively, and the ring leads 229, 230 and 231 are connected to the commutator bars 233, 237 and 241 by the leads 253, 254 and 255, respectively. For convenience of showing there are included the dashed lines at the sides of the leads 250, 251 and 252 to emphasize the division locations between the successive coil units "A," "B" and "C."

The commutator bars subtend equal angular embracements, being 30 degrees each, corresponding to the sub-sections. There are indicated the two slip rings 256 and 257 which rotate with the rotor element. The brushes 258 and 259 are connected to said slip rings by the leads 260 and 261, respectively, said brushes also being carried by and rotating with the rotor element. A source of D.C. is shown in the form of the battery 262. The terminals of this battery connect to the brushes 263 and 264 by the leads 265 and 266, respectively, said brushes bearing against the slip rings 256 and 257, respectively. Thus current is supplied through the stationary brushes 263 and 264 and the rotating slip rings 256 and 257, to the rotating brushes 258 and 259 to the stationary commutator bars, and from them to the stationary stator exciting coil sections. Conveniently the brushes 258 and 259 may be carried by a carrier which can be rocked about the rotor axis to thereby adjust the angular positions of the brushes as a pair, with respect to the angular positions of the rotor teeth, so as to ensure a proper and desired relation between the rotor teeth and the commutation points. The mechanical means to enable such angular adjustments are not herein illustrated since they may be of conventional form.

The structural details of the coil elements have not been illustrated in FIGURE 6. However, by reference to FIGURE 1 it will be apparent that each of the main coils "A," "B" and "C" of FIGURE 1 may be divided into two sections by either a horizontal or a vertical plane of division, thus providing the two coil sections within a common annular space, and corresponding to the sections "AA" and "AAA" of FIGURE 1, for example, in place of the single unit "A" of FIGURE 1. Then the proper taps and connections may be provided to the coil sections so provided. The commutator and brush and slip ring elements may also be provided at one end of the motor unit according to well understood and conventional practice.

It will be seen that by such subdivisions of the main exciting coils as disclosed in FIGURE 6 it is possible to obtain an operation closely simulating the operating effects of supply of wave form currents such as shown in FIGURE 5, for example. Thus very smooth torque effects will be produced, but in combination with the novel functions herein disclosed.

It is stated that the shaft 208 shown in FIGURE 4 may comprise the motor shaft itself, so that with the disclosures of that figure it is possible to obtain self-commutation or proper progressive excitation of the various stator coils. In FIGURE 4 there is also shown the button 267 carried by said shaft 208 so that, when the unit of FIGURE 4 is not physically connected to the motor itself, the rotations and control of the shafts 208 and 211 may be effected manually or otherwise, producing the desired current impulses which will then be correctly delivered to the stator coils and in proper sequence and controlled timing. Thus a remote control of the excitations of the stator coils will be produced, the several coils "A," "B" and "C" of FIGURE 4 being located in the motor and

at a distance from the unit shown in FIGURE 4. This is also true of the arrangement shown in FIGURE 6.

Reference may now be had to FIGURES 17 and 18 in which there is shown another embodiment similar in general to that shown in FIGURE 4. In the case of FIGURES 17 and 18 the motor is generally designated as 268, and the various gear elements, commutator and brush unit, and similar parts are designated by numerals generally the same as used in FIGURE 4. However, in the present case there is shown the commutator as provided with double the number of segments shown in FIGURE 4, being six in number; and there are shown these segments 268, 269, 270, 271, 272 and 273 as cross connected in opposite pairs by the leads 274, 275 and 276. These cross connections are then connected to the free ends of the stator exciting coils "A," "B" and "C" by the leads 277, 278 and 279, respectively. The other ends of the coils are then connected to the common lead 280, comprising one side of the source of current. The other side of such source of current connects by the lead 281 to the brush 282 which bears against the commutator. The current is thus supplied to the several stator coils in proper sequence. In this arrangement the commutator segments are twice the number of the motor sections, so that the "multiple" heretofore mentioned is "two."

In FIGURE 17 there is shown the commutator shaft 220 as provided with the phasing handle 283 so that the phasing of the commutator bars may be readily adjusted from time to time by a simple adjustment. It will be noted that by such phasing adjustment from one operating position to and through the neutral brush position, to an operating position at the opposite side of such neutral position, it is possible to actually reverse the motor operation. Furthermore, by adjustment of the phasing it is possible to produce operations in which the excitations of the several stator coils are carried beyond the rotor positions of exact registration of rotor teeth with the stator teeth, so that overlaps are produced in the torque forces developed on the rotor. If the phasing setting of such commutator shaft be such that current is cut off from one coil at the condition of exact registry of the rotor teeth of such motor section with the stator teeth of such motor section, with simultaneous excitation of the stator coil next in the sequence, it is evident that no dragging effect will be produced by an "overlapping" of the excitation of the earlier coil after the position of exact registry of the teeth has occurred. By shifting the handle 283, however, far enough, such an overstaying operation may be produced, with corresponding hold-back on the rotor element. Such an operation may be desired for certain operations.

Referring again to FIGURE 18 there is therein shown a capacitor 284 and resistor 285 connected in series shunt with each of the stator coils "A," "B" and "C." By selection of proper impedance values for these capacitors and resistors, in comparison to the impedance effects of the so bridged excitation coils, it is possible to produce time constants for the excitations and de-magnetizations of the main coils, to ensure either fast or slow de-magnetization responses of the magnetic effects produced between the rotor and stator teeth. Thereby it is possible to ensure either very fast responses, corresponding to ability to produce very quick rotor advancements, or the responses may be substantially slowed down, thus producing a correspondingly slow rotor response to each excitation or signal. The inclusion of the resistor 285 in series with the capacitor and such series being bridged across the stator coil, the discharging of the capacitor may be substantially slowed down so that the demagnetization of the stator poles may be correspondingly delayed. Thus it is possible to produce a combination in which the magnetization of the stator teeth will occur very rapidly upon closing the circuit to the coil for such teeth, followed by a retention of full magnetization as long as such circuit remains closed, followed by a slowed decay of the magnetization when the circuit to such coil is opened.

Thereby the current may be sustained in the coil even after the circuit is opened, thus sustaining the magnetization to produce an overlap of the excitation of the coil of the next section or to approach the instant at which such next section excitation will occur.

It will now be illuminating to consider some modes of operation of the motor of FIGURE 17 with the circuit arrangements of FIGURE 18. First let us consider that the motor is under heavy load both frictional and inertial. Now if the input terminals are connected to direct current and with the phasing handle 283 in the proper position, the motor will slowly accelerate in a given direction. The motor will continue to accelerate until the impedance of the coils will not allow enough of a current rise in a motor section when the teeth are in the best relation to exert sufficient force for further acceleration. By adjusting the phasing handle so that the commutator will allow current to be switched to the coils so that the current will have time to rise to a sufficient maximum while the rotor and stator teeth are at an optimum relation will also further increase acceleration.

If now the phasing handle 283 is further adjusted so that the flux becomes a maximum as the rotor teeth are leaving the stator teeth of the successive sections, a braking action will take place and the rotor will be rapidly decelerated. If the phasing handle is left in this position, the motor will go through the stationary position and begin to accelerate in a reverse direction. If desired, however, a further adjustment of the phasing handle when the rotor is substantially stationary will cause the commutator to switch current to the section where the stator and rotor teeth are in alignment and the rotor will lock in such position. In these operations of the motor the capacitors will serve primarily in an anti-sparking capacity or function.

The motor of FIGURE 17 may also be operated by connecting the input terminals to a source of pulses of current. The motor in this case advances one step for each pulse, the phasing lever being properly set. If the motor is intended for counting pulses, there being little or no external load on the motor, it may be desirable to improve its manner of operation by adding an appropriate frictional load to the motor by means of the frictional clutch 317 (shown in FIGURE 17). This comprises the brake disk 318 carried by the stationary stud 319 and screw-threaded on said stud as shown in FIGURE 17 so that the frictional drag may be adjusted or calibrated, together with the rotor shaft driven friction disk 320 which is spring pressed against the disk 318 by the adjustable spring 321.

Without such a frictional load, when the rotor has been accelerated by the current pulse, the inertia can carry the rotor considerably beyond the alignment of stator teeth and rotor teeth. The duration of the current must therefore be longer so that the rotor does not continue to rotate and is brought back to the proper position for the next pulse. With the frictional load, however, the duration of the pulse may be increased, and therefore the rate of counting may be increased, the frictional load being adjusted to a value which is optimum to give this result.

For a counting operation the capacitors may perform an additional function to that of preventing sparking of the commutator contacts. With the capacitors of correct capacity the duration of the input pulses need be only long enough to charge the capacitor in circuit at each pulse. The current from the capacitor can then be sufficient to ensure completion of the corresponding step of the rotor. Thus pulses of short duration can be counted as well as pulses of longer duration.

The speed at which the motor may count depends on the rapidity with which the rotor can make a step. The steps can be exceedingly rapid when the rotor has a low inertia and a small angular movement per step. Although the duration of a pulse to make the motor advance one step may be exceedingly short when use is

made of the capacitors, the current delivery through the coil must be of such short duration that it has ceased when the movement of the rotor has brought the contactor elements to their next position of circuitry. When

5 the next capacitor is charged, the rotor will advance another step. In line with the foregoing, if direct current is applied to the motor under the foregoing conditions, the motor will advance step-by-step at a substantially constant rate. This rate can be controlled by the size of 10 the capacitors used, the larger capacitors being associated with the lower rates.

The control arrangements so far described serve to supply to the stator coils current impulses of regularly recurring kind. It is to be noted, however, that various

15 important uses of motors embodying the features of invention include the delivery of single pulses or groups of pulses, to the coils, to thereby produce corresponding rotor advances for such purposes as counting, and the like. There are now described certain embodiments 20 whereby the impulses may be severally controlled from a distance, as during the counting of digits, recording various steps of an operation, and like purposes. References may be had to FIGURES 16, 19, 20 and 21 disclosing one such embodiment.

25 In FIGURE 21 there are shown three stator coils "A," "B" and "C" (together with the capacitors and resistors such as shown in FIGURE 18 bridged across each stator coil). There are also shown, schematically, the leads 286, 287 and 288 extending leftward from the free ends of

30 these coils, and the common return lead 289 connected to the right-hand ends of the coils. The lead 289 connects to one side of a source of D.C. current, such as the battery 290. Each of the leads 286, 287 and 288 may be considered as representing a development of a circular conductor, with the ten contacts 291 connected to each 35 of such circular or ring shaped conductors. For clarity these contacts 291 are designated as 291^a, 291^b, and 291^c for the three conductors 286, 287, and 288, respectively. In this figure there are also shown the movable sets of

40 contacts 292, 293 and 294 for the contacts 291 of the three sets connected to the three conductors 286, 287 and 288. For clarity these contacts 292, 293 and 294 are shown with the suffixes "a," "b" and "c," corresponding to the conductors 286, 287 and 288, respectively. The 45 three contacts of each of these sets are carried by a common carrier which may move from station to station along the conductors 286, 287 and 288 (actually moving circularly since the conductors 286, 287 and 288 actually comprise circular conductors as above explained. These carriers actually rotate in harmony with the rotor 50 rotations). The contacts 292^a, 292^b and 292^c, are connected to a common lead 295, the contacts 293^a, 293^b and 293^c, are connected to a common lead 296, and the contacts 294^a, 294^b and 294^c, are connected to a common lead 297. The free end of the source of current, the battery, is connected by the lead 298 to the three switch elements 299, 300 and 301, respectively, which control connection of the lead 298 with the three leads 295, 296 and 55 297, respectively.

Examination of FIGURE 21 will show that the contacts 291 are vertically aligned with each other in sets, each set including a contact to each of the leads 286, 287 and 288. Also, that the movable contacts 292 are stepped rightwardly, counting downwardly from the lead 286 to the lead 287, to the lead 288; that the contacts 293 are also stepped rightwardly, counting downwardly from the lead 286 to the lead 287, to the lead 288; and that the contacts 294 are also stepped rightwardly, counting downwardly from the lead 286 to the lead 287, to the lead 288. These 60 steppings or spacings are such that when the contact 292^a is engaged with one of the contacts 291^a, the other contacts 293^a and 294^a are set back one-third of the spacing between the successive contacts 291^a, and two-thirds of such spacing, respectively, so that rightward movement of the carrier will first open the contact 292^a 65 from one of the contacts 291^a, with which it was engaged,

then will bring the contact 293^a into engagement with one of the contacts 291^a, then will open the contact 293^a from such contact 291^a, and finally will bring the contact 294^a into engagement with one of the contacts 291^a, then will open the contact 294^a from such contact 291^a. Examination of this figure will also show that similar contacting engagement and disengagement will occur for the other carrier contacts "b" and "c" in regular order through the groups.

In the position shown in FIGURE 21 the contact 292^a is seen to be engaged with the contact 291^a, the contact 293^b with the contact 291^b, and the contact 294^b with the contact 291^c. All of the switches 299, 300 and 301 are however, open. Accordingly, none of the circuits of the coils "A," "B" and "C" is actually closed. Reference will now be made to FIGURE 1 to complete the description and understanding of the operation now to be described.

In FIGURE 1 it is seen that the left-hand rotor section is in such position that upon energizing the stator coil "A" the rotor will be drawn clockwise to bring the teeth of such left-hand rotor section into complete registry with the corresponding stator teeth. Accordingly, by closing the switch 299 (of FIGURE 21), with energization of the stator coil "A," the rotor will be moved substantially one-third of a tooth spacing to bring the left-hand rotor section teeth into complete registry with the corresponding stator teeth; and at the same time the rotor teeth of the central section will move clockwise away from the stator teeth with which they have been registered, and the rotor teeth of the right-hand section "C" will move clockwise into position preparatory to being drawn into registry with the next set of stator teeth of the section "C" under proper excitation conditions. Therefore, if after having closed the switch 299 just long enough to cause such stepping advancement of the rotor, such switch now be opened and then the switch 299 be again closed a further forward step of the rotor will occur since such second closing of the switch 299 will now energize the stator coil "C" (the contacts 292^c, 293^c and 294^c having been advanced rightwardly by the first operation). Finally a third such closing of the switch 299 will result in a third clockwise step of the rotor, the carrier having been shifted rightwardly a still further step, thus, successive closings and openings of the switch 299 will result in successive clockwise steppings of the rotor. It should be here noted that in case the switch 299 should be held in its closed position the rotor will continue to step rightwardly or clockwise by steps at a rate dependent on various of the rate affecting conditions which have been previously discussed hereinbefore.

Further exploration of the operations of this arrangement will show that successive closings and openings of the switch 301 will result in successive counterclockwise steppings of the rotor element. Also, that closing of the switch 300 will result merely in exciting the stator coil "B" at which motor section the rotor teeth are completely registered with the stator poles, thus producing no torque action, and merely serving to magnetically lock the rotor in its then position.

It will be understood that the switches 299, 300 and 301 may be located at any convenient control position, and may be operated by any suitable device with which the motor is to be combined and operated.

In FIGURES 16, 19 and 20 there is shown in fragmentary form a mechanical structure capable of effectuating the proper contact movements to enable functioning according to the operations just explained in connection with the description of FIGURE 21. The rotor shaft 302 is extended sufficiently to carry the insulating sleeve 303 on which are mounted the three slip rings 295^b, 296^b and 297^b. The source of current—the battery 290 in the present case—is shown in FIGURE 16, with one terminal connected to the lead 298. Also, the three switches 299, 300 and 301 are shown in FIGURE 16. The brushes 295^a, 296^a and 297^a of FIGURE 16 correspond to por-

tions of the leads 295, 296 and 297 of FIGURE 21. These brushes engage the slip rings 295^b, 296^b and 297^b, which slip rings in turn connect to the leads 295^c, 296^c and 297^c extending inwardly through the shaft (which is provided with a suitable bore to accommodate said leads). The other terminal of the battery connects to the lead 289. For simplicity of illustration and to avoid confusion there are shown only the stator coil "A" in this figure, and there are also shown only the contacts needed to control that coil's excitation.

The arcuate segment 286^a simulates a portion of the lead 286 shown in FIGURE 21. Said segment carries the inwardly extending contact fingers 291^{aa}, corresponding to the contacts 291^a of FIGURE 21. A disk of insulation material 304 is carried by the shaft of the rotor; and the three contacts fingers 292^{aa}, 293^{aa} and 294^{aa}, extend outwardly from such disk within a plane normal to the axis of rotation, and substantially in line with the contacts 291^{aa}. These fingers 292^{aa}, 293^{aa} and 294^{aa} are spaced with respect to each other according to the principles already explained with respect to the spacing of the contacts 292, 293 and 294 with respect to each other and with respect to the contacts 291^{aa} of the ring element 286^a. It will be understood that in actuality the other stator coils "B" and "C" would also be connected to the lead 289, that two other ring shaped conductors similar to the conductor 286 would be provided with their inwardly extending fingers, and that two other sets of the fingers 292^{aa}, 293^{aa} and 294^{aa} would be provided, connected to the leads 295^c, 296^c and 297^c, respectively. Thus the schematic showing of FIGURE 21 would be duplicated in a physical structure of which FIGURE 21 is but a portion. It is thus unnecessary to describe the operation of the showing of FIGURE 16 further.

FIGURES 19 and 20 are a fragmentary longitudinal section through the arrangement shown in FIGURE 16, and a fragmentary cross-section corresponding thereto. Their description in detail is deemed unnecessary in view of what has already been explained.

It is remarked that in the showing of FIGURE 21 there are included the capacitor and resistor combinations bridged across the several stator coils, according to the principles described in connection with the showing of FIGURE 18.

In FIGURES 22 and 23 there is shown another arrangement for effecting "commutation" of the current impulses to the several stator coils in proper sequence. In this case there is shown the rotor shaft 305 carrying the disk of insulating material 306 at a location outside of the stator housing. The three microswitches 307, 308 and 309 are mounted to a convenient element around the disk 306. These microswitches are provided with the small buttons which are engaged by an element to reverse their biased spring leaf contacts according to conventional designs. There are not shown these details in FIGURES 22 and 23, beyond showing the buttons 310 projecting slightly beyond the switch housings. The disk 306 is provided with dwells 311, 312 and 313 around its periphery, and other dwells not numbered are also shown. The microswitches are set at positions around the disk such that the several microswitches will be actuated in proper sequence to produce the desired sequence and timing of the excitations of the stator coils. In view of the detailed descriptions already given it is deemed unnecessary to further describe the present arrangement.

In FIGURE 24 there is shown another modified means to produce desired time delay constants in the operations of the stator coils. In this case there are shown the capacitor 314 bridged across a portion of the coil, and another capacitor 315 and resistor 316 in series bridged across the entire body of the coil. The effects of such an arrangement will be readily understood by one skilled in the arts.

Reference has been made to the use of laminated pole 75 and tooth constructions for reduction of eddy current

losses and other well understood advantages. Such type of construction will generally be found advantageous for frequencies of substantially 400 c.p.s. For very high frequencies it may be found desirable to use polar and tooth constructions formed of sintered finely granular magnetic material highly compacted by large pressures, as is well understood in the magnetic arts. Such forms of construction may be found desirable for use with frequencies of the order of 1000 c.p.s. and higher.

Attention is called to the fact that the embodiment shown in FIGURES 13 and 14 which incorporates the axially aligned type one features combined with the sub-gap features, also presents the further feature that the body portions of the two stator tooth carriers for the single section illustrated in such figures are formed of magnetic material, the exciting coils being set into such stator body portions. Then the hub portions of such magnetic material body elements are also of magnetic material but separated from each other to accommodate the hub portion 169 of the corresponding rotor element. This rotor hub portion is also of magnetic material, and small gaps are provided between the rotor hub portion and the proximate stator hub portions. These gaps may be made small since there is no possibility of lateral deflections of the rotor hub portion which is locked to the shaft and such shaft may be readily held against endwise shifts with respect to the stator or body of the motor. Accordingly, with this combined arrangement it is possible to secure the benefits of the axially aligned stator and rotor teeth feature, together with the benefits of large radius of the rotor teeth with corresponding torque benefit, and the further benefit of bringing the exciting coils to small radius values for specified ampere turns. These features may or may not be further combined with the benefits of the sub-gap feature which is more completely disclosed in said parent application, Serial No. 443,798, now Patent No. 2,797,346, of which case the present is a divisional case thereof.

It is claimed:

1. In an electric motor, the combination of stator and rotor elements, means to journal said elements co-axially with respect to each other, the stator element including a plurality of sections not less than three spaced in succession axially of the motor, each stator element including a plurality of stator poles spaced equidistant around the axis of the motor and at the same radius from said axis, the rotor element including a plurality of sections equal to the number of stator sections, each rotor section including a plurality of teeth spaced equidistant around the axis of the motor and at the same radius from said axis, the number of rotor teeth of each section being equal to the number of stator poles of such section, the teeth of each rotor section being simultaneously in full registry with the poles of the companion stator section for each angular advance of the rotor equal to 360 divided by the number of rotor teeth of such section, and the teeth of the several rotor sections being successively in full registry with the poles of the companion stator sections with progress of such full registry of the rotor teeth and companion stator poles of the sections in successive cycles of such full registry conditions of the sections, magnetizing coils for the several sections, each coil when energized generating a magnetomotive force producing flux flow between all of the poles of the corresponding stator section and all of the teeth of such rotor section, together with commutation means to electrically energize the magnetizing coils in succession, said commutation means including a commutator having a number of commutation elements equal to a full multiple of the number of motor sections, connections between the commutation elements and the coils in a progression around the commutator corresponding to cyclic progress of energization of the motor sections which have full registry of their rotor teeth and stator poles, and with one cycle of electrification of the stator coils for each cyclic electrification of the commutation elements, and means to electrify the commutation elements in said cycle of progress.

2. In an electric motor, the combination of stator and rotor elements, means to journal said elements co-axially with respect to each other, the stator element including a plurality of sections not less than three spaced in succession axially of the motor, each stator element including a plurality of stator poles spaced equidistant around the axis of the motor and at the same radius from said axis, the rotor element including a plurality of sections equal to the number of stator sections, each rotor section including a plurality of teeth spaced equidistant around the axis of the rotor and at the same radius from said axis, the number of rotor teeth of each section being equal to the number of stator poles of such section, the teeth of each rotor being simultaneously in full registry with the poles of the companion stator section for each angular advance of the rotor equal to 360 divided by the number of rotor teeth of such section, and the teeth of the several rotor sections being successively in full registry with the poles of the companion stator sections with progress of such full registry of the rotor teeth and companion stator poles of the sections in successive cycles of such full registry conditions of the sections, magnetizing coils for the several sections, each coil when energized generating a magnetomotive force producing flux flow between all of the poles of the corresponding stator section and all of the teeth of such rotor section, together with commutation means to electrically energize the magnetizing coils in succession, said commutation means including a commutator having a number of commutation elements equal to a full multiple of the number of motor sections, connections between the commutation elements and the coils in a progression around the commutator corresponding to cyclic progress of energization of the motor sections which have full registry of their rotor teeth and stator poles, and with one cycle of electrification of the stator coils for each cyclic electrification of the commutation elements, and means to electrify the commutation elements in said cycle of progress, together with operative connections between the rotor and the means which electrifies the commutation elements in said cycle of progress, said operative means being constituted to electrify the commutation elements in a cyclic recurrence with electrification of each stator magnetizing coil a number of times equal to the number of stator teeth in each section, during each full rotation of the rotor.
3. Means as defined in claim 2, wherein said multiple is one.
4. Means as defined in claim 2, wherein the operative connections between the rotor and the means which electrifies the commutation elements in the cycle of progress includes means to change the angular position of said means which electrifies the commutation elements, with respect to the rotor.
5. Means as defined in claim 2, wherein the commutation elements comprise commutator bars, and wherein the means to electrify the commutation elements in said cycle of progress comprises at least one brush and means to support the same for cyclic movement with respect to the commutator bars, and wherein the operative connections between the rotor and the means which electrifies the commutation elements in said cycle of progress comprises a driving connection between the motor and said brush.
6. In an electric motor, the combination of stator and rotor elements, means to journal said elements co-axially with respect to each other, the stator element including a plurality of sections not less than three spaced in succession axially of the motor, each stator element including a plurality of stator poles spaced equidistant around the axis of the motor and at the same radius from said axis, the rotor element including a plurality of sections equal to the number of stator sections, each rotor section including a plurality of teeth spaced equidistant around the axis of the motor and at the same radius from said axis, the number of rotor teeth of each section being equal to the number of stator poles of such section, the teeth of each rotor being simultaneously in full registry with the poles of the companion stator section for each angular advance of the rotor equal to 360 divided by the number of rotor teeth of such section, and the teeth of the several rotor sections being successively in full registry with the poles of the companion stator sections with progress of such full registry of the rotor teeth and companion stator poles of the sections in successive cycles of such full registry conditions of the sections, magnetizing coils for the several sections, each coil when energized generating a magnetomotive force producing flux flow between all of the poles of the corresponding stator section and all of the teeth of such rotor section, together with commutation means to electrically energize the magnetizing coils in succession, said commutation means including a commutator having a number of commutation elements equal to a full multiple of the number of motor sections, connections between the commutation elements and the coils in a progression around the commutator corresponding to cyclic progress of energization of the motor sections which have full registry of their rotor teeth and stator poles, and with one cycle of electrification of the stator coils for each cyclic electrification of the commutation elements, and means to electrify the commutation elements in said cycle of progress.

to the number of stator poles of such section, the teeth of each rotor being simultaneously in full registry with the poles of the companion stator section for each angular advance of the rotor equal to 360 divided by the number of rotor teeth of such section, and the teeth of the several rotor sections being successively in full registry with the poles of the companion stator sections with progress of such full registry of the rotor teeth and companion stator poles of the sections in successive cycles of such full registry conditions of the sections, magnetizing coils for the several sections, each coil when energized generating a magnetomotive force producing flux flow between all of the poles of the corresponding stator section and all of the teeth of such rotor section, together with commutation means to electrically energize the magnetizing coils in succession, said commutation means including a first defined current conductor in connection with each stator coil, a series of second defined current supply connections equal in number to the number of stator coils, a group of movable first defined current conductor electrifying elements for each first defined current conductor, each such group including a number conductor electrifying means equal to the number of stator coils, separate current supply connections between the movable current conductor electrifying elements of each group and the second defined current supply connections, operative control connections between the rotor and all of said conductor electrifying means of said groups effectively to actuate all of the conductor electrifying means of each group to establish electrifying connection of each of the conductor electrifying means of such group with the corresponding first defined current conductor sequentially during each full rotation of the rotor a number of times equal to the number of poles of the corresponding motor section, said operative control connections being constituted to actuate the conductor electrifying means of all of the groups in successive phase relationship such that the first defined current conductor for each stator coil is in electrifying connection with each of the second defined current supply connections sequentially during rotor tooth movement between successive stator poles, and being such that the first defined current conductors for all of the stator coils are individually in electrifying connection with separate ones of the second defined current supply connections, together with switching means to selectively supply current to the second defined current supply connections.

7. Means to accelerate a body having a large mass to drive said body at a pre-determined speed, said means including an electric motor having stator and rotor elements, means to journal said elements co-axially with respect to each other, the stator element including a plurality of sections spaced in succession axially of the motor, each stator element including a plurality of stator poles spaced equidistant around the axis of the motor and at the same radius from said axis, the rotor element including a plurality of sections equal to the number of stator sections, each rotor section including a plurality of teeth spaced equidistant around the axis of the motor and at the same radius from said axis, the number of rotor teeth of each section being equal to the number of stator poles of such section, the teeth of each rotor section being simultaneously in full registry with the poles of the companion stator section for each angular advance of the rotor equal to 360 divided by the number of rotor teeth of such section, and the teeth of the several rotor sections being successively in full registry with the poles of the companion stator sections with progress of such full registry of the rotor teeth and companion stator poles of the sections in successive cycles of such full registry conditions of the sections, magnetizing coils for the several sections each coil when energized generating a magnetomotive force producing flux flow between all of the poles of the corresponding stator section and all of the teeth of such rotor section, a driving element in

driving connection with said mass, and driving connections between the rotor of the motor and said driving element, said driving connections including a flexible coupling having an input element, an output element, and a flexible element connecting said input and output elements, a driving connection between the rotor and the input element of the coupling, a driving connection between the output element of the coupling, and means to supply current to the magnetizing coils of the stator in a progressive sequence to produce a succession of driving impulses of the rotor shaft and the input element of the coupling with yield of the flexible element, said driving impulses being in the same direction of drive.

8. Means as defined in claim 7, wherein the means which supplies current to the magnetizing coils of the stator is constituted to deliver the current to the coils individually and in said progressive sequence.

9. Means as defined in claim 8, wherein the supply of current to each coil in such sequence terminates not later than the commencement of supply of current to the next coil of the sequence.

10. Means as defined in claim 8, wherein the supply of current to each coil in such sequence terminates before the commencement of supply of current to the next coil of the sequence.

11. Means as defined in claim 8, wherein the supply of current to each coil in such sequence terminates after the commencement of supply of current to the next coil of the sequence.

12. The combination of a stepping motor and means to improve the accuracy of operation of said motor, comprising an electric motor having stator and rotor elements, means to journal said elements co-axially with respect to each other, the stator element including a plurality of sections spaced in succession axially of the motor, each stator element including a plurality of stator poles spaced equidistant around the axis of the motor and at the same radius from said axis, the rotor element including a plurality of sections equal to the number of stator sections, each rotor section including a plurality of teeth spaced equidistant around the axis of the motor and at the same radius from said axis, the number of rotor teeth of each section being equal to the number of stator poles of such section, the teeth of each rotor section being simultaneously in full registry with the poles of the companion stator section for each angular advance of the rotor equal to 360 divided by the number of rotor teeth of such section, and the teeth of the several rotor sections being successively in full registry with the poles of the companion stator sections with progress of such full registry of the rotor teeth and companion stator poles of the sections in successive cycles of such full registry conditions of the sections, magnetizing coils for the several sections each coil when energized generating a magnetomotive force producing flux flow between all of the poles of the corresponding stator section and all of the teeth of such rotor section, means to supply current to the magnetizing coils of the stator in a progressive sequence to produce a succession of driving impulses of the rotor element, a drag torque producing element in connection with the rotor element, and means to adjust the drag torque of such drag torque element.

13. Means as defined in claim 12, wherein said succession of current supply to the magnetizing coils includes reversals of the order of progress of such succession of driving impulses.

14. Means as defined in claim 12, wherein said succession of current supply to the magnetizing coils produces a continuous succession of unidirectional driving impulses.

15. In an electric motor, the combination of stator and rotor elements, means to journal said elements co-axially with respect to each other, the stator element including a plurality of sections spaced in succession axially of the motor, each stator element including a plurality of stator

poles spaced equidistant around the axis of the motor and at the same radius from said axis, the rotor element including a plurality of sections equal to the number of stator sections, each rotor section including a plurality of teeth spaced equidistant around the axis of the motor and at the same radius from said axis, the number of rotor teeth of each section being equal to the number of stator poles of such section, the teeth of each rotor section being simultaneously in full registry with the poles of the companion stator section for each angular advance of the rotor equal to 360 divided by the number of rotor teeth of such section, and the teeth of the several rotor sections being successively in full registry with the poles of the companion stator sections with progress of such full registry of the rotor teeth and companion stator poles of the sections in successive cycles of such full registry conditions for the sections, magnetizing coils for the several sections, each coil when energized generating a magnetomotive force producing flux flow between all of the poles of the corresponding stator section and all of the teeth of such rotor section, together with means to deliver electrical impulses to the magnetizing coils, the teeth of each rotor section comprising at least one block of sintered finely granular magnetic material highly compacted by large pressures.

16. In an electric motor, the combination of stator and rotor elements, means to journal said elements co-axially with respect to each other, the stator element including a plurality of sections spaced in succession axially of the motor, each stator element including a plurality of stator poles spaced equidistant around the axis of the motor and at the same radius from said axis, the rotor element including a plurality of sections equal to the number of stator sections, each rotor section including a plurality

of teeth spaced equidistant around the axis of the motor and at the same radius from said axis, the number of rotor teeth of each section being equal to the number of stator poles of such section, the teeth of each rotor section being simultaneously in full registry with the poles of the companion stator section for each angular advance of the rotor equal to 360 divided by the number of rotor teeth of such section, and the teeth of the several rotor sections being successively in full registry with the poles of the companion stator sections with progress of such full registry of the rotor teeth and companion stator poles of the sections in successive cycles of such full registry conditions for the sections-magnetizing coils for the several sections, each coil when energized generating a magnetomotive force producing flux flow between all of the poles of the corresponding stator section and all of the teeth of such rotor section, together with means to deliver electrical impulses to the magnetizing coils, the poles of each stator section comprising at least one block of sintered finely granular magnetic material highly compacted by large pressure.
